UNITED STATES PATENT OFFICE

2,258,532

DESK SUPPORT

William J. Bargen, Waukegan, Ill.

Original application July 26, 1939, Serial No. 286,699. Divided and this application March 13, 1940, Serial No. 323,799

8 Claims. (Cl. 155—128)

This invention relates to desk structures and is a division of my copending application, Serial No. 286,699, filed July 26, 1939, for Offset pedestal desk.

An object of this invention is to provide an improved desk including a book holding compartment and a means for supporting the desk and the compartment from the seat.

Another object of this invention is to provide an improved desk support which is secured at its lower portion to one side of a seat and at its upper portion to the desk and which includes means whereby the desk or top including the book support may be vertically adjusted relative to the seat.

A further object of this invention is to provide a support of this kind which is so constructed that vertical adjustment of the desk relative to the seat will simultaneously shift the desk or top including the book compartment forwardly or rearwardly with respect to the seat.

A still further object of this invention is to provide a combined desk support and book compartment which is carried by the desk support and is adjustable relative to the seat with the adjustment of the support.

A further object of this invention is to provide in a desk, a top supporting standard which is positioned at one side of the seat and is vertically adjustable through the medium of adjustable interengaging or locking elements which are automatically locked together in their adjusted position by the offset weight of the desk with respect to the support.

A further object of this invention is to provide a vertically adjustable desk and support therefor wherein the adjusting means will support the desk in its adjusted position irrespective of the condition of the locking or holding means for the adjusting means.

A further object of this invention is to provide a means whereby the desk element may be adjusted relative to the seat so that the desk may be angularly adjusted with respect to the seat irrespective of the angular relation of the seat relative to the floor.

A further object of this invention is to provide an adjusting means for the desk relative to the seat wherein the adjusting and supporting means is at one side of the desk and seat so as to permit free entrance to the seat from one side thereof.

A further object of this invention is to provide a desk having readily removable supporting devices which if broken may be easily replaced

without making it necessary to replace the entire desk and seat structure.

A further object of this invention is to provide a desk structure wherein the top including the book compartment where such is used may be rocked upwardly by pressure from below without affecting the adjustment, as where a student forces the top upwardly with his knees, thus forming a shock absorbing feature in the desk to relieve the remaining structure of undue strain.

A further object of this invention is to provide in a desk structure means for detachably supporting the top from the seat so that when the desks are not in use, they may readily be removed from the seat and stacked or stored one upon the other with the base of a superposed desk engaging the top of a lower desk, thus permitting unused desks to be placed out of the way.

20 Embodying the objects aforesaid and others which may hereinafter appear, the invention consists of the novel construction, combination and arrangement of parts as will be more specifically referred to and shown in the accompanying drawings, wherein is illustrated embodiments of the invention, but it is to be understood that changes, variations and modifications may be resorted to which fall within the scope of the invention as claimed.

30 In the drawings:

Figure 1 is a vertical section of a desk top including a book compartment and a support therefor which is mounted on a seat, the seat being shown in side elevation and broken away.

35 Figure 2 is an enlarged fragmentary sectional view taken on the line 2—2 of Figure 1.

Figure 3 is a fragmentary side elevation of one of the desk supporting members.

Figure 4 is a sectional view taken on the line 40 4—4 of Figure 1.

Figure 5 is a top plan partly broken away and in section of a modified form of desk supporting structure embodying a non-adjustable stem showing the adaptation thereof with respect to a desk top, illustrated in dotted lines and broken away.

Figure 6 is a detail front elevation partly broken away of the structure shown in Figure 5.

50 Figure 7 is a fragmentary enlarged sectional view taken on the line 7—7 of Figure 5.

Figure 8 is a detail side elevation of still another modified form of desk supporting element.

Figure 9 is a sectional view taken on the line 55 9—9 of Figure 2.

Figure 10 is a sectional view taken on the line 10—10 of Figure 1.

Figure 11 is a fragmentary sectional view through one of the end walls of the desk, and Figure 12 is a bottom plan view of the supporting bracket.

Referring to the drawings the numeral 15 designates generally a seat structure which is supported from a base similar to that embodied in my copending application, Serial No. 286,699. The side edges of the seat are reinforced by oppositely disposed angle-shaped members 15^a, only one shown, which are secured in position by the holdfast means 15^b. A desk or top supporting member generally designated as 16 is secured to the seat 15 at one side thereof. The supporting member or bracket 16 comprises a lower upwardly and forwardly inclined fixed member 17 and an upper movable and adjustable member 18. The lower member 17 is provided in an outer side wall 19 thereof with a gear rack 20 extending upwardly from the lower portion thereof and preferably the outer side wall 19 is provided with an inturned lower end portion 21 forming a stop to limit the downward movement of the adjustable member 18.

A substantially horizontally disposed plate 22 is formed integral with the lower tubular supporting member 17 and is adapted to engage beneath the seat 15 as shown in Figure 2, being fixed to the seat 15 by one or more fastening devices 23. The plate 22 (Figures 2 and 10) is disposed substantially at right angles to the inner side wall 24 of the lower supporting member 17 and arranged transversely with respect to the lower face of the seat 15. A bracing web 25 is formed integral with the rear side 26 of the lower member 17 and an upwardly projecting flange or plate 27 is formed integral with the web 25 and projects beneath and is disposed lengthwise with respect to the seat 15 as shown in Figures 9 and 10, being secured to the seat 15 by at least one fastening member 23^a. The flange 27 is disposed at right angles to the flange or plate 22, forming with the flange 22 a right angle or said plates 22 and 27 correlate to provide what may be termed an L-shaped member which engages beneath the seat 15. Preferably the flange or plate 22 is provided with a pair of downwardly extending bracing flanges 28 and 29, more clearly shown in Figure 9. The upper face of the flange or plate 22 is arranged above the upper face of the flange or plate 27 (Figure 9). An offset combined clamping and bracing member (Figure 2) in the form of an angle bar 30 is adapted to engage between the flanges 28 and 29 on the underside of the plate 22, extending transversely across the underside of the seat 15 as shown in Figure 2. One of the fastener members 23 secures the bar 30 against the lower face of the plate 22.

The movable bracket member 18 is formed with a rear wall 31 and a front wall 32, having a vertically disposed slot 33 extending longitudinally thereof and opening through the lower end of the front side 32, Figure 3. An outer side wall 34 and an inner side wall 35 connect the rear and front sides 31 and 32, respectively, together. The outer side face of the outer side wall 34 of member 19 is provided adjacent the lower end thereof with a pair of teeth 36 which are adapted to selectively engage the teeth 29 of a stationary rack formed on the inner face of the wall 19 of the stationary member 17. A set screw 37 is carried by the upper end portion of the lower member 17, being threaded through the inner wall 24 of

the lower member 17 and is adapted to engage against the wall 35 of the member 13 so as to bind the upper member 18 relative to the lower member 17 after the adjustment of the member 18. The set screw 37 also provides a means whereby in case of serious schoolroom abuse in excess of normal in which there is a noticeable deflection of the seat or top, the relative position of the movable stem or upper member 18 under the top and the lower member 17 can be readily corrected. In front elevation the bracket or support 16 extends vertically from the seat 15 while in side elevation the bracket or supporting member 16 is inclined to the vertical being inclined upwardly and forwardly. The wall 34 has its lower portion inset as at 34^a and on the lower end of this inset portion is arranged the teeth 36. The member 18 is open at its bottom. The wall 24 of the member 17 has its upper portion 24^a inset and has a threaded opening 24^b with which the set screw 37 threadably engages. The supporting member or bracket 16 may be termed a supporting post, as well as elements 18^a, 18^b to be referred to.

The movable member 18 is adapted to be clamped in its vertically adjusted position relative to the lower stationary member 17 by means of a clamping block 38 which is substantially T-shaped in transverse section and is formed of a body portion and stem portion. The body portion is arranged within the member 18 and the stem portion engages in the slot 33. A pair of clamping bolts 39 extend through the front wall 43 of the lower member 17 and are threaded into the body part and stem of the clamping block 38.

The book box or article supporting member 41 is similar to the structure embodied in my Patent No. 2,165,125 which issued July 4, 1939 and it comprises a substantially corrugated bottom wall 42, a front wall 43, a rear wall 44, a side wall 45 and a side wall 52. Preferably the front wall 33 is arcuate in transverse section and inclined upwardly and rearwardly from the front edge of the bottom wall 42. The side wall 45 is formed integrally with the upper end of the adjustable bracket member 18 and such end is formed with a pair of oppositely disposed flanges 46, 46^a. The flange 46 engages beneath the bottom wall 42, and the flange 46^a abuts the rear wall 44. The front wall 43 at its upper end is provided with a reverted upper edge 47 forming a reinforcing upper edge for the front wall 43. The flanges 46, 46^a are disposed at an oblique angle with respect to each other. The side wall 45 on the inner side thereof is provided adjacent the forward end with an inwardly projecting lug 48 upon which the reverted portion 47 engages and a fastening member 49 tightly holds the reverted portion 47 on the lug 48. This reverted portion 47 forms a relatively short top wall for the book member 41 extending rearwardly from the front wall 43 so as to prevent the positioning of books within the holder 41 to a height beyond the top wall or reverted portion 47. This lip or reverted portion 47 also provides a means to eliminate torsional strain or weave on the hinge for the top 53 and also on the lugs 48 and 51. The lug 51 is carried by the side wall 52 which is opposite from the side wall 45. This torsional strain or weave occurs by reason of the fact that one hinge arm 53 may be under greater frictional strain than the other hinge arm, after the desk has been used for some time. A top forming a desk member 58 is adapted to engage the free end of the book compartment or holder 41 and is constructed in

the form of a flat board. The top 50 is hingedly secured to the compartment or book holder 41 by means of a pair of L-shaped arms 53 having one leg 54 thereof provided with a base bar 55 which is adapted to be secured by fastening members 56 to the underside of the desk member 50. The other leg 57 of a hinged arm 53 is pivotally mounted on a pivot 58 which is carried by one of the side walls of the holder 41 and the arm 57 is frictionally held against swinging movement by friction devices as more specifically set forth in my copending application filed of even date herewith.

A bumper 59 is secured to the front edge of the desk or top as shown in Figure 1 and comprises a metal bar 60 which is enclosed in a rubber covering 61. The bar 60 is provided with a plurality of inwardly projecting flanges 62 which are fastened by fastening devices 63 to the underside of the top 50.

In Figure 8 there is disclosed a modified form of upper bracket or top supporting member which comprises a stem or movable support 18^a which is similar to the support 18, being provided with a pair of teeth 36^a for engagement with teeth 20 in a lower supporting member similar to the support 17. The stem or supporting arm 18^a has formed integral with the upper end thereof a supporting bar 64 which is adapted to engage beneath the top and the supporting member 64 has secured thereto a right angularly disposed top supporting bar similar to that shown in Figures 5 and 6. The structure shown in Figure 8 is adapted to be substituted for the book compartment 41 and the desk top 50 together with the stem 31 shown in Figure 1. The stem 18^a is adapted to engage in the lower tubular support 17 of Figure 1 and to be locked in adjusted position by the clamping and locking means shown in Figures 1, 2 and 4.

In Figures 5, 6 and 7, there is disclosed a further modification of this invention which includes a lower supporting member 17^b and an upper supporting member 18^b which is integral with the lower supporting member 17^b. The upper supporting member 18^b has formed integral therewith a top supporting bar or plate 64^a and a right angularly disposed supporting bar 65 is formed integral with the upper end of the upper supporting member 18^b and extends laterally from the supporting member 64^a. An angle bar 66 is secured adjacent one end thereof by fastening devices 68 to the supporting bar 65. The fastening devices 68 engage through one side 67 of the angle member 66 and the upper side 69 of the angle member 66 is adapted to be secured as by fastening devices 70 to the underside of a top member 50^a, Figure 5. An inwardly projecting supporting member or base 22^a is formed integral with the lower end of the support 17^b and this base or supporting member 22^a is constructed similar to the plate 22 including the two flanges 28 and 29 together with the right angle plate 27 as is shown in Figures 2, 9 and 10.

In the use and operation of this desk and supporting structure, the supporting bracket 16 is adapted to be secured by the fastening devices 23 to the seat 15 at one side thereof. Preferably the supporting bracket 18 is secured to the right hand edge or side of the seat 15. The telescoping and vertically adjustable member 18 is adapted to be adjusted relative to the lower stationary member 17 by initially loosening the clamping block 33, then the set screw 37 is adjusted outwardly so as to permit rocking of the adjustable

member 18 relative to the stationary member 17. The movable member 18 may then be either raised or lowered by disengaging the teeth 36 of the movable member 18 with selected teeth of the rack 20 and then either raising or lowering the movable member 18. When the movable member 18 has been vertically adjusted, the bolts 39 are tightened so as to tighten the clamping bar 38. In the event the top 50 is not substantially horizontal or is not substantially parallel with the seat 15, the set screw 37 may be adjusted either inwardly or outwardly before the clamping member 38 is tightened by the bolts 39.

With a structure of this kind the offset weight of the top 50 and the book holder 41 will hold the teeth 36 in engagement with the selected teeth 20 of the lower member 17 irrespective of whether the clamping member 38 is loose or tight. In the event it is desired to use a top or desk without a book compartment the structure shown in Figure 8 may be substituted for the adjustable member 18 shown in Figure 1. Where the structure shown in Figure 8 is used, the additional supporting bar structure shown at 65 and 66 in Figures 5, 6 and 7 may also be used so as to support the top from the upper end of the adjustable member 18^a.

Where it is desired to use a desk or top structure without having a vertically adjustable top, the structure shown in Figures 5 to 7, inclusive, may be substituted for the structure shown in Figures 1 and 2.

Where a book compartment and desk is not desired, the structure shown in Figure 8 may be substituted therefor, it being only necessary to remove the upper part 18 from the lower support 17 and insert the part 18^a in the support 17.

Due to the inclination of the bracket or support 16 which is forwardly and upwardly when the movable member 18 is raised so as to permit additional space between the top 50 and the seat 15, the rear edge of the top 50 will simultaneously be moved forwardly thus permitting additional body room between the rear edge of the top 50 and the back of the seat. With a construction of this kind, the top 50 can be readily adjusted to accommodate students of different physical characteristics so that a desk of this type may be used if necessary through the school period of a student, thus making it unnecessary to purchase or have on hand chairs or desks of different sizes. The top 50 is provided on its underside with cushioning members 71 in the form of buttons which are adapted to engage the upper edge of the side walls 45 and 52.

The desk and seat hereinbefore described will not only provide a proper seat for the student, but will also promote good posture. This structure will also permit the use of a maximum number of desks in a minimum of space, which is a very essential factor in schools, auditoriums and the like having only a limited amount of space available. The maximum number of students can, therefore, be accommodated in a limited space and when this space is desired for other than classroom purposes, the desks can be stacked one upon the other.

Furthermore, where the funds available for the purchase of the desks will not permit the purchase of the desks with the book compartments, the structure shown in Figures 5 to 7 or Figure 8 may be used. By making the several parts of the desk interchangeable, broken or worn parts may easily be replaced at small expense or the more expensive book compartment structure may

be substituted for the initially purchased desk which includes the structure shown in Figure 8.

The seat, back and base structure embodied in my copending application, supra, can be used as a foundation, and any desired top structure can be mounted thereon depending on the needs of the students or the funds available for purchase of the top structure.

What I claim is:

1. In a desk including a seat and a top, means supporting said top relative to the seat comprising an inner and an outer tubular member disposed in telescopic relation, said outer member being stationary, said inner member being lengthwise shiftable relative to the outer member, means for securing the lower end of the outer member to said seat, means for securing the upper end of the inner member to one side of said top, interengageable teeth within said supporting means being arranged on opposed faces of said members for sustaining the inner member in adjusted position, said inner member being slotted, and clamping means including parts arranged in said inner member and slot and parts arranged in said outer member and threadably engaging with the said other parts for clamping other opposed faces of said members together for securing said inner member in adjusted position relative to said outer member.

2. In a desk including a seat and a top, means supporting said top relative to the seat comprising an inner and an outer tubular member disposed in telescopic relation, said outer member being stationary, said inner member being lengthwise shiftable relative to the outer member, means for securing the lower end of the outer member to said seat, means for securing the upper end of the inner member to one side of said top, interengageable teeth within said supporting means being arranged on opposed faces of said members for sustaining the inner member in adjusted position, said inner member being slotted, clamping means including parts arranged in said inner member and slot and parts arranged in said outer member and threadably engaging with the said other parts for clamping other opposed faces of said members together for securing said inner member in adjusted position relative to said outer member, and adjustable means threadably engaging with said outer member for abutting the inner member to thereby adjust the angular relation of said inner member relative to said outer member.

3. In a desk including a seat and a top, means supporting said top relative to the seat comprising an inner and an outer tubular member disposed in telescopic relation, said outer member being stationary, said inner member being lengthwise shiftable relative to the outer member, means for securing the lower end of the outer member to said seat, means for securing the upper end of the inner member to one side of said top, interengageable teeth within said supporting means being arranged on opposed faces of said members for sustaining the inner member in adjusted position, said inner member being slotted, and clamping means including parts arranged in said inner member and slot and parts arranged in said outer member and threadably engaging with the said other parts for clamping other opposed faces of said members together for securing said inner member in adjusted position relative to said outer member, said inner member having one of its walls inset and provided with

the teeth for interengagement with the teeth on the outer member.

4. In a desk including a seat and a top, means supporting said top relative to the seat comprising an inner and an outer tubular member disposed in telescopic relation, said outer member being stationary, said inner member being lengthwise shiftable relative to the outer member, means for securing the lower end of the outer member to said seat, means for securing the upper end of the inner member to one side of said top, interengageable teeth within said supporting means being arranged on opposed faces of said members for sustaining the inner member in adjusted position, said inner member being slotted, clamping means including parts arranged in said inner member and slot and parts arranged in said outer member and threadably engaging with the said other parts for clamping other opposed faces of said members together for securing said inner member in adjusted position relative to said outer member, and adjustable means threadably engaging with said outer member for abutting the inner member to thereby adjust the angular relation of said inner member relative to said outer member, said outer member having an inset portion provided with a threaded opening for the said angular adjusting means carried by such member.

5. In a desk including a seat and a top, means supporting said top relative to the seat comprising an inner and an outer tubular member disposed in telescopic relation, said outer member being stationary, said inner member being lengthwise shiftable relative to the outer member, means for securing the lower end of the outer member to said seat, means for securing the upper end of the inner member to said top, said inner member having an inset part opposing in spaced relation a part of the outer member, said parts being provided with interengageable teeth for sustaining the inner member in adjusted position, clamping means arranged in said members for clamping opposed faces of said members together for securing said inner member in adjusted position relative to said outer member, said outer member having an inset upper portion, and adjustable means carried by said inset upper portion and engaging the inner member to thereby adjust said inner member in angular relation with respect to said outer member.

6. In a desk including a seat and a top, a lengthwise adjustable supporting post interposed between said seat and top formed of an inner and an outer section disposed in telescopic relation, said outer member including at its lower end a pair of inwardly extending plates disposed below the seat and arranged at right angles to each other, one of said plates disposed transversely and the other lengthwise with respect to the seat, means for securing one of said plates to the seat, the other of said plates being formed with a pair of spaced depending flanges, an angle-shaped bar arranged between said flanges, means for securing said angle bar, said other plate and said seat together, said inner member being formed with a pair of parts at its upper end disposed at an oblique angle with respect to each other and secured to said top, and means for securing said post in lengthwise adjusted position.

7. In a desk including a seat and a top, a supporting post vertical in front elevation and inclined to the vertical in side elevation, said post being disposed between the seat and top for sup-

porting the latter relative to the seat, said post having means at its upper end for securing it to said top, said post being formed at its lower end with a pair of right angularly disposed plates arranged below the seat and one extending transversely with respect to the seat and the other lengthwise with respect to the seat, means for securing that plate extending lengthwise of the seat to the latter, that plate extending transversely of the seat being formed with a pair of depending flanges, an angle bar arranged between said flanges, and means for securing said angle bar to that plate extending transversely of the seat and such plate and the seat together.

8. In a desk including a seat and a top, a post disposed between the seat and the top for sup-

porting the latter, said post formed at its lower end with a rearwardly extending web, an inwardly extending plate at the lower portion of the post arranged below and disposed transversely with respect to the seat, an inwardly extending plate integral with the web arranged below and extending lengthwise of the seat, a pair of flanges depending from that plate disposed in transverse relation with respect to the seat, an angle bar extending between said flanges, means for securing that plate disposed in lengthwise relation with respect to the seat to the latter, and means for securing said angle bar to the plate extending transversely of the seat and such plate and the seat together.

WILLIAM J. BARGEN.
